UNITED STATES PATENT OFFICE.

JOHN JAMES BARKER, OF COWANSVILLE, QUEBEC, CANADA.

SIGN.

1,286,194.

Specification of Letters Patent. Patented May 14, 1918.

Application filed December 15, 1917. Serial No. 207,366.

To all whom it may concern:

Be it known that I, JOHN JAMES BARKER, a subject of the King of Great Britain, and resident of the town of Cowansville, in the 5 Province of Quebec, in the Dominion of Canada, have invented certain new and useful Improvements in Signs, of which the following is the specification.

The invention relates to improvements in 10 signs as described in the present specification and illustrated in the accompanying drawings that form part of the same.

The invention consists essentially of the 15 novel formation of a sign of paper material, preferably card or paste board, whereby the pores or interstices thereof are effectively closed and the sheet rendered impervious to moisture as well as reinforced generally.

20 The objects of the invention are to devise a sign that will replace metal and other signs and be quite efficient for advertising any particular wares, to cheapen the cost of material in the production of indoor and 25 outdoor signs, to furnish a sign which will withstand the inclemencies of the weather, and generally to provide a cheap, durable and serviceable sign.

In the drawings, Figure 1 is a plan view 30 of the sign.

Fig. 2 is an exaggerated cross sectional view.

Fig. 3 is a cross sectional view of a specially reinforced style of this sign.

35 Like numerals of reference indicate corresponding parts in each figure.

Referring to the drawings, the numeral 1 indicates a sheet of comparatively thin 40 card board, which may be of any shape and of any size.

This card in its original state and cut to the proper size is printed by lithographic or other process with the design lettering or other matter containing the announcement desired.

The card is now taken and treated with 45 a transparent glue 2 with a holding strength of one hundred and thirty pounds to the square inch.

50 This glue is applied over the surface containing the printed matter, and also on the back of the sign, preferably by means of a calendering machine, the lower roll dipping in a glue well and smearing the glue over the surface of the paper and the upper pressure roller driving said glue by a pressure

of approximately 200 pounds into the pores or interstices of the card board.

The preferable mixture in dissolving the glue is ten parts glue and three parts water. 60

The temperature at which the application of the glue is made is one hundred and fifty degrees Fahr. and it is advisable to run the card four times through the rolls for each surface. 65

The card is now permitted to dry for a period of three hours or so and then a wax oil filler 3 is applied to the back only of the card by the same or a similar machine and this substance stops up the pores 70 or other interstices and forms a coating as well without affecting to any material extent the flexibility of the card.

The card is again put to dry for a period of two hours or so. 75

The face of the card over the printer's ink and glue is now painted with a varnish 4 composed of one gallon of enamel varnish to one pint of bleached linseed oil and then allowed to dry for twenty-four hours or so. 80

Both the wax oil and the varnish are applied at room temperature. The sign is bound by the metal strip 5, which is first rolled on to the ends and then to the top and bottom edges, though it is not essential, 85 as to the manner of application, for the signs may be of so many different shapes.

The holes 6 for the hanging nails or tacks may be placed any where, through the binding strips and card therein inclosed. 90

In Fig. 3 the card board is reinforced by a mill board, the binding strips including both card and mill board, the latter firmly attached to the former by a coat of glue.

It will be seen by the description in detail hereinbefore, that a sign is produced quite impervious to moisture and therefore one that can be used in any exposed position besides the finish obtained in a sign made as explained is excellent and will remain 100 in that condition for a lengthy period. Furthermore the materials are so simple and cheap, that really work of the first quality is turned out at the most moderate prices and the handling greatly facilitated by 105 reason of the light weight of the article produced.

Various changes may be made in carrying out this invention without departing from the spirit thereof, so long as they remain 110 within the claims, for novelty following.

What I claim is:—

1. An out door pasteboard sign having printed matter thereon forming an announcement and a transparent weatherproof covering of a substance adapted to take form and enter and cap the pores on one side and further a weatherproof covering of a substance on the other side adapted to do likewise, the unprotected edges being closed from exposure to the weather by strips of metal folded over opposite edges and further folded over the other edges and over the aforesaid strips.

2. A sign, comprising a sheet of paper board material having on one side a printed design in contrasting colors, a substance applied to the back adapted to cap and fill

the pores or other interstices and spread therearound and therebetween and thereby form a waterproof coating flexible in its 20 consistent state, a mill board backing forming a reinforcement and glued to said paper board, a metal binding strip joining said mill and paper boards at the edges, and a clear varnish covering the front of said 25 bound boards and through which said design appears.

Signed at the city of Montreal, Quebec, Canada, this 5th day of December, 1917.

JOHN JAMES BARKER.
